UNITED STATES PATENT OFFICE.

FRANK C. GIVENS, OF TUOLUMNE, CALIFORNIA; CLARA B. GIVENS ADMINISTRATRIX
OF SAID FRANK C. GIVENS, DECEASED.

CARBURETOR.

Application filed September 13, 1926. Serial No. 135,242.

This invention relates to an improved carburetor and has for an object to provide a construction wherein the liquid fuel is caused to change direction while in the presence of moving air before it enters a combustion chamber.

Another object of the invention is to provide an improved carburetor wherein control valves are arranged at the air inlet and air and fuel outlet.

A further object of the invention is to provide a carburetor wherein the float operates a valve for preventing an excess supply of fuel liquid to the carburetor when the same is being supplied under gravity.

In the accompanying drawing—

Figure 1 is a longitudinal vertical sectional view through a carburetor disclosing an embodiment of the invention.

Figure 2 is a sectional view through Figure 1, approximately on line 2—2.

Figure 3 is a fragmentary horizontal sectional view through Figure 1 on line 3—3.

Referring to the accompanying drawing by numerals, 1 indicates the bowl of a carburetor and 2 the mixing chamber which is adapted to be connected at one end with means for utilizing the explosive mixture supplied by the carburetor. The end 3 is adapted to be connected with the intake manifold of an internal combustion engine or to be otherwise suitably connected with the cylinders of the engine so that when the engine is turned over or is operating, explosive mixture will be drawn from the mixing chamber 2. The mixing chamber 2 is provided with tubular members 4 and 5 merging into a central section 6 which preferably has an integral central post 7. The liquid from the bowl 1 is discharged from the pipe 8 into the mixing chamber 2 near the post 7 and in fact, in such a manner as to cause some of it to strike the post, though most of which will be immediately taken up by the air passing through the tubular section 5. Butterfly valves 9 and 10 are provided in the tubular sections 4 and 5, said valves being controlled by suitable rods whereby they may be opened and closed as desired. It will be noted that the valve 10 regulates the amount of air passing into the mixing chamber while valve 9 regulates the outflow of explosive mixture. It is, of course, evident that if valve 10 is open and valve 9 is closed or almost closed, only a small amount of air may enter.

The post 7 merges into an auxiliary post 11, said post 11 being in effect one structure and hollow so as to accommodate the rod 12 which has a pointed end 13 and a threaded section 14. This rod acts as a needle valve 60 and may be readily adjusted by the thumb member 15 connected to the rod at the outer end. The hollow post 11 is provided with passage-ways 16 and 17 near the bottom of the bowl or reservoir 1.

When the needle valve or rod 12 is in the position shown in Figure 1, no liquid can flow from the reservoir or bowl 1. When the pointed end 13 is unseated more or less, some of the liquid may flow through the opening 18 into the pipe 19 and through the various sections of this pipe through pipe 8 where it is discharged into the mixing chamber which mixes with the air before entering the intake manifold of the engine. It will 75 be noted that the upper edge of the bowl 1 is seated in an annular groove 20 while the lower edge is clamped by the nut 21 screwed onto the lower end of post 11 whereby the bowl is firmly clamped in position, the arrangement producing an air-tight connection. A gasket 22 is arranged adjacent nut 21 so as to prevent any leakage at this point. A float of cork or other material 23 is provided in the bowl 1 and is swingably supported by a 80 hinge structure 24. A rod 25 is connected to float 23, said rod carrying a valve member 26 adapted to be moved against the seat 27 which forms an enlargement of pipe 28.

When the liquid 29 is lowered, float 23 will 90 naturally swing downwardly under the action of gravity and move the valve member 26 away from its seat whereby pipe 28 is open and liquid may pass therethrough into the bowl 1. Pipe 28 is connected with a supply 95 pipe 30 which is connected to a suitable supply reservoir 30 arranged at any desired point, as for instance, the rear of an automobile. Sometimes the tank or reservoir 31 is arranged to cause the liquid fuel to flow by gravity through pipe 30 and from thence into bowl 1. When this arrangement is used, the float 23 is very important as it causes the closing of valve 26 and thus limiting the amount of fuel in the bowl. Where the bowl 1 is supplied through the action of suction, the liquid fuel will flow through pipes 30 and 28 when a sufficient rarefaction is provided in the bowl 1, said rarefaction being produced by the suction of the cylinders of the engine 100 110

to which the carburetor is secured. Ordinarily, when the parts are in the position shown in Figure 2, the air in the upper part of the bowl is under atmospheric pressure and the valve 26 is slightly open so that when the engine is turned over or started, liquid fuel may be readily drawn from the carburetor and as the same is drawn from the carburetor suction will be produced which will cause a new supply of liquid fuel to be drawn into the bowl 1. A cup 32 is provided which is supplied with a valve 33, said valve in turn being connected with bowl 1 preferably above the float whereby a supply of liquid fuel may be inserted into the carburetor whenever desired, as for instance, when the carburetor is first installed.

As the engine operates it will produce a rarefaction or suction in the mixing chamber 2 so that air is drawn therein and also liquid fuel which will quickly mix with the air and will divide as it passes the post 7. This dividing of the sprayed liquid and also the air, causes an independent carburetion on each side of the post 7 and later this independently carbureted fuel is mixed before it passes valve 9 whereby a very efficient carburetion is produced before the mixture enters the intake manifold of the engine to which the carburetor is connected. The mixture may be readily changed at any time by adjusting the rod or needle valve 12. Also, a slight variation in mixture may be provided by a proper manipulation of valves 9 and 10. If valve 10

is shut off completely so that very little air enters, the engine will draw liquid fuel in the usual manner which will mix with the small amount of air passing valve 10 and will thereby produce a very rich mixture. If the valve 10 is open fully and the valve 9 almost closed, substantially a reverse action will be produced and the mixture will be very poor.

What I claim is:

A carburetor, comprising means forming a mixing chamber formed with a central hollow post, an inlet at one end and an outlet at the opposite end, said means being also formed with a tubular extension projecting at right angles to said mixing chamber, said tubular extension being in free communication with said hollow post, said tubular extension having apertures in its sides near the end thereof opposite said hollow post and a valve seat surrounding a discharge opening near said apertures, a hand operated valve extending through said hollow post and into said tubular extension for co-acting with said seat to control the flow of fuel passing out through said discharge opening, means forming a float chamber positioned to be in communication with said apertures, tubular means forming a passage-way from said discharge opening to said mixing chamber, and valves co-acting with said inlet and said outlet for controlling the entrance of air into the mixing chamber and the discharge of explosive mixture from the mixing chamber.

FRANK C. GIVENS.
